UNITED STATES PATENT OFFICE.

WILLIAM J. WEILAND, OF INDIANAPOLIS, INDIANA.

FURNACE RADIATOR.

Application filed June 14, 1926. Serial No. 115,859.

This is an invention relating to means for increasing the radiating surface within a furnace and is particularly adaptable to furnaces for household heating purposes and the like employing an oil burner.

It is the usual procedure in installing an oil burner to employ the present furnace with the customary combustion chamber and radiating dome above, but with such installation, particularly where the oil is atomized by air pressure there is a resultant high stack loss, as the air forced into the furnace rushes through the combustion chamber, and into the stack thereby carrying out an undue amount of heat that is so lost on account of sufficient radiating surface not being present between the combustion chamber and the stack, and it is the primary purpose of providing a radiating unit that may be easily and cheaply interposed within the furnace between the combustion chamber and the stack.

Reference is made to the accompanying drawing, in which—

Fig. 1, is a rear elevation of the radiating unit;

Fig. 2, a top plan view of the radiating unit;

Fig. 3, a transverse section through the radiating unit on the line 3—3 in Fig. 1; and

Fig. 4, a fragmentary side elevation of a furnace with the radiating unit in place.

Like characters of reference indicate like parts throughout the several views.

Referring first to Fig. 4, of the drawing, a furnace of simplified construction is here shown to illustrate in a more or less diagrammatic manner the installation of the radiating unit in reference to the furnace parts. The furnace here shown has the usual and well known central heater 10 with the gas and smoke outlet through the top into the pipe 11 and the heater 10 is surrounded by the housing 12 with the usual air space therebetween such that air may pass about the heater 10 to be heated and out through the riser holes 13. The housing 12 is made as usual out of a plurality of vertically joined sections which are bolted together at the joints, not shown.

A smoke pipe 14 leads from the pipe 11, and customarily leads directly to the stack (not shown), but in this invention, such a stack connection is not made, and instead,

the pipe 14 leads forwardly to an upper 55 manifold 15 having a continuous passage therearound.

A plurality of flues 16 extend downwardly from the top manifold 15 to discharge into a substantially U-shaped manifold 17 below, and a discharge pipe 18 leads from the lower manifold 17 to any suitable stack connecting means.

Referring again to Fig. 4, an oil burner tube 19 is shown projecting into the combustion heater 10 near the bottom. Such tube may be introduced into the heater 10 at a higher elevation as indicated by the dotted lines if desired. In either event, the combustion of the oil takes place within the 70 heater 10 and the hot gases, including the excess air used to atomize the oil and not required to support combustion, pass upwardly out through the pipe 11, the pipe 14, and into the top manifold 15, from which the 75 gases are distributed to escape downwardly through the flues 16 into the lower manifold 17 and finally be discharged outwardly through the pipe 18.

It is obvious that a large heated surface 80 including both top and bottom manifolds and flues is thus exposed within the furnace housing 12 to radiate the heat therefrom and warm the air passing through the housing and thus utilize heat that would otherwise 85 be lost.

It is to be noted that the manifolds 15 and 17 are shaped so as to permit the radiating unit to be slipped about the outside of the heater 10. This is accomplished by unbolting the sections at their vertical joints and lifting as many of the sections away as may be found necessary. Then the manifold unit is raised until its top member 15 will clear the pipe 14, and by a sliding side 90 movement the manifold unit is put in proper vertical relation with the furnace and then lowered to final position as shown in Fig. 4. The end of pipe 14 is inserted in the pipe 11, and then the housing sections are replaced with the pipe 18 passing through the housing as shown in Fig. 4, and the pipe 18 is connected with the chimney in the usual manner.

Having described my invention in one 105 particular form, I do not desire to be limited to the precise structure so shown, nor any more than may be required by the fol-

lowing claim, since it is obvious that many structural variations may be had without departing from the spirit of the invention.

I claim:

- 5 In a furnace, the combination with an outer housing and a combustion chamber within the housing having a reduced top discharge, of an integral detachable radiating unit comprising an upper continuous annular tube, a lower manifold tube, substantially U-shaped to receive the combustion chamber between the legs of said last member and a plurality of flues interconnecting the two manifold tubes the top one receiving a discharge from the combustion chamber and the lower one discharging to the stack outside of the housing, said radiator unit being adapted for assembly with the combustion chamber by removing the housing, passing the top manifold tube over the reduced top discharge of the combustion chamber and a leg of the lower tube on each side of the combustion chamber and then lowering the manifold unit to operating position with the top tube surrounding the reduced top discharge of the combustion chamber. 20 25

In testimony whereof I affix my signature.

WILLIAM J. WEILAND.
